UNITED STATES PATENT OFFICE.

ALVA B. WRIGHT, OF RAMSEY, ILLINOIS.

BUNDLING-MACHINE.

1,102,844.

Specification of Letters Patent.

Patented July 7, 1914.

Application filed March 12, 1914. Serial No. 824,208.

To all whom it may concern:

Be it known that I, ALVA B. WRIGHT, a citizen of the United States, residing at Ramsey, in the county of Fayette and State of Illinois, have invented certain new and useful Improvements in Bundling-Machines; and I do declare the following to be a full, clear, and exact description of the invention, such as will enable others skilled in the art to 10 which it appertains to make and use the same.

This invention relates to new and useful improvements in bundling or baling machines and more particularly to a machine 15 for bundling empty cement bags, and the primary object of the invention is to provide a machine or apparatus by means of which empty bags or sacks may be conveniently formed into bundles of suitable sizes and 20 securely held while being tied.

A further object of the invention resides in providing a machine which may be readily handled by one person to accomplish work which ordinarily requires the efforts of a number of persons, and still another object resides in providing a machine, which is simple and durable in construction, inexpensive to manufacture, and one which will be very efficient and useful in operation.

With these and other objects in view, the invention consists in the novel features of construction, combination and arrangement of parts as will be hereinafter referred to 35 and pointed out in the specification and claims.

In the accompanying drawings, forming a part of this application: Figure 1 is a plan view of a device constructed in accordance with my invention; Fig. 2 is a side elevation thereof with the bending bar shown in dotted lines in a position engaged with the locking lugs; Fig. 3 is a similar view showing the bending or engaging arms in 40 their raised positions; Fig. 4 is an end elevation of the device in the position as shown in Fig. 2; Fig. 5 is a similar view of the device as disposed and shown in Fig. 3; Fig. 6 is a transverse section through the 45 device as seen on lines 6—6 of Fig. 3 looking in the direction of the arrows; Fig. 7 is an enlarged detail section through the spaced uprights; and Fig. 8 is a bottom plan view 50 of the device.

In describing the invention, I shall refer

to the drawings in which similar reference characters designate corresponding parts throughout the several views and in which—

1 indicates a base member which, as shown is of rectangular plate like formation but 60 which, of course, may be of any desired shape and size, as desired, and secured to the under face of the base adjacent the ends thereof, are the supporting leg members 2. Secured to the upper face of this base mem- 65 ber 1 at the ends thereof, are pairs of spaced uprights or standards 3, the purpose of which will be hereinafter and more particularly set forth.

Secured to the upper face of the base 1 70 immediately adjacent the pairs of standards or uprights, are the spring bands 4 which project some distance beyond the side edges of said base member, the securing point between said bands and base member being 75 substantially midway of the ends of said bands. Secured to the outer ends of the bands are the bars 5. Also engaged with the upper face of the base member 1 are the flexible members 6 such as linked chains or the 80 like, said chains being engaged with the base member intermediate of their ends and the free ends of said linked chains are secured to the side bars 5 which, as stated, are carried on the outer ends of the spring bands 85 4. These flexible members or chains 6 are arranged at equal distances from one another between the spring bands 4, and together with said spring bands, form the major portion of the bundling device. It 90 might here be stated also that the spring bands 4 are bowed somewhat downwardly.

In the bundling of the bags, the bars 5 are raised to abut the uprights 3 and I have provided an improved means for accomplishing this result. To this end, the uprights 3 are each slotted transversely as shown at 7 and in the slotted portion of each upright is rotatably mounted a pair of rollers indicated as 8 and 9, the former 100 being disposed just above the latter. A pair of flexible members 10 such as cables or the like are provided and disposed through the alining slots 7 of the pairs of uprights 3 to be trained over the upper pulleys 8 therein. Portions of the connections are then disposed inwardly and around the lower pulleys 9, then drawn upwardly through the slots 7, the extreme free ends 105 of said connections being engaged with the 110

side bars 5, as clearly shown in the drawings. From this construction, it will be seen that a portion of each flexible connection 10 is disposed through the space between the pairs of uprights 3 and by forcing downwardly on these portions of the connections 10 to form a loop therein, it is obvious that said side bars will be drawn upwardly toward the uprights 3. For this purpose, I provide a rod or bar 11 which is of a length greater than the length of the base 1 and is adapted to normally rest on the portions of the flexible connections 10 disposed between said pairs of uprights 3. One end of this rod or bar 11 is designed to form a handle as indicated at 12 for the purpose of withdrawing the bar or rod when desired.

Fulcrumed about centrally on the under-face of the base 1 is a lever 13, the fulcrum point being disposed adjacent one end of said lever, and engaged with the lever on opposite sides of this fulcrum point, are the additional flexible connections 14 which extend in opposite directions toward the ends of the base 1. The end edges of the base 1 have secured thereto the straps 15 which are looped intermediate of their ends as shown at 16 to form bearings for pulleys 17 and said flexible connections 14 are trained over said pulleys to permit the free ends of said connections to project above the plane of the upper face of said base. The free ends of these connections 14 are provided with hooks 18 which are designed for engagement with the rod or bar 11, so that when the lever 13 is actuated in one direction, said rod or bar may be drawn downwardly toward the base 1. A ratchet 19 is also arranged on the under face of the base 10 adjacent the fulcrum point of the lever and a spring detent 20 is provided on the lever for engagement with said ratchet. A handle operating means 21 is provided in connection with the outer end of said lever for the actuation of said detent and as the lever projects outwardly beyond one side edge of the base, the same may be readily applied to use by the operator. In view of the spring detent and ratchet, it will be understood that said lever will be held in any position to which the same is adjusted.

In operation, assuming that the device is in a position ready for operation, a plurality of sacks such as cement bags or the like, 55 piled one upon the other, are mounted on the upper face of the base 1 over the flexible connections or chains 6. The bar 11 is then disposed between the spaced uprights 3 to rest on the portions of the connections 10 disposed therebetween and said bar is then manually forced downwardly to a predetermined point. At this particular point, stop members 22 are provided with which said bar may be engaged. It will be understood 60 65 from the construction of the device, that

upon the downward movement of said bar, loops will be formed in the flexible connections 10 between the pairs of uprights 3, thus drawing upon said connections and drawing upwardly upon the side bars 5. 70 With such movement of said side bars, the flexible connections or chains 6 will be drawn tightly around the sacks or bags disposed thereon and when said bar is engaged with the stop members 22, the device is held in such position temporarily. The lever 13 is then released by being moved in one direction, and the flexible connections 14 are drawn so that the hooks 18 at the ends thereof may be engaged with the bar or rod 80 85 90 95 100 105 able partially around said last mentioned element in opposite directions thereto and simultaneously therewith.

4. In a bundling machine, a base, a dividing bar movable vertically with respect thereto, upwardly movable bending arms on the base for coöperation with said dividing bar, and means for raising said arms to their operative positions simultaneously

10 with the lowering of said bar.

5. In a bundling machine, a base, a dividing bar movable vertically with respect thereto, upwardly movable bending arms carried on the base for coöperation with said bar, spring means in connection with said arms to normally retain the latter in their lowered and inoperative positions, and means for raising and lowering said arms simultaneously upon the lowering and raising

20 of said bar.

6. In a bundling machine, a base, a dividing bar movable vertically with respect thereto, cradle-like arms carried on the base and movable upwardly and inwardly with respect thereto, flexible connections between said cradle-like arms, spring means in connection with said arms to normally retain the same in their lowered and outspread positions, and means for operating said arms simultaneously with and in opposite directions to said dividing bar.

7. In a bundling machine, a base, a dividing element movable vertically with respect thereto, bow springs secured to the base and having the ends projecting beyond the sides thereof, bars secured to the free ends of said bow springs, flexible connections between said bars, and means for moving said bars upwardly and inwardly upon the lowering

40 of said dividing element.

8. In a bundling machine, a base, uprights mounted at the ends thereof, bow springs secured to the base and having the ends thereof projected beyond the sides of said base, bars secured to the ends of said springs, flexible binding members engaged with said bars and projected therebetween, flexible members engaged at their ends with the ends of said bars and having connection with

50 said uprights, a vertically movable member engaged with said flexible connections adja-

cent the uprights and adapted, upon being lowered, to dispose the bars upwardly and inwardly against the tension of said springs, and means for lowering said vertically movable member, the latter forming a dividing element and the bars with the binding members therebetween forming a bending element for coöperation with the dividing element.

9. In a bundling machine, a base, pairs of spaced apart uprights mounted at the ends thereof, pulleys rotatably mounted on the uprights, cradle-like arms mounted on the base and movable upwardly and inwardly with respect thereto, spring means in connection with said arms to normally retain the latter in their lowered and outspread positions, flexible connections trained over the pulleys on said uprights and engaged at their ends with the outer ends of said arms, and a member movable vertically between the pairs of spaced uprights and engaged with portions of flexible connections whereby to raise said arms upon the lowering of said member, and means for lowering said member.

10. In a bundling machine, a base, pairs of spaced uprights mounted at the ends thereof, pulleys mounted on said uprights, spring actuated cradle-like arms mounted on the base and movable upwardly and inwardly with respect thereto, said arms being normally held in their lowered and outspread positions, flexible connections engaged with the outer free end portions of said arms and trained over the pulleys on said uprights, and means vertically movable through the pairs of spaced uprights for engagement with portions of said flexible connections, whereby to raise said arms to their operative positions, said last mentioned means forming a dividing means, and said arms forming a bending means for coöperation therewith.

In testimony whereof I have hereunto set my hand in presence of two subscribing witnesses.

ALVA B. WRIGHT.
